GEORGE S. GATCHELL, OF ROSELLE PARK, NEW JERSEY, ASSIGNOR TO THE SINGER MANUFACTURING COMPANY, OF ELIZABETH, NEW JERSEY, A CORPORATION OF NEW JERSEY.

PRESSER FOOT FOR SEWING MACHINES.

Application filed June 29, 1926. Serial No. 119,296.

This invention relates to presser-feet for sewing machines and has for an object to provide a presser-foot which is specially adapted to cooperate with a four-motion feed-dog in uniformly feeding work having lumps or cross-seams, and which will control the work to prevent the skipping of stitches.

Many attempts have heretofore been made to provide a presser-foot for satisfactorily handling work of this character and while some of such attempts have met with a measure of success on work of light to medium thicknesses, none of the prior presser-feet with which I am familiar will ride over heavy cross-seams with a uniform stitch-length feeding action and without assistance by the operator in pulling on the work in rear of the sewing point.

In the usual felled seam, for example there are four thicknesses of material where the edges of the material interlock and twelve to sixteen thicknesses of material where cross-seamed portions overlap or interlock. Hence a thick lump is encountered at such a cross-seam, and such lump is with considerable difficulty passed under presser-feet such as have heretofore been constructed.

To overcome the difficulty in question I have provided a presser-foot of novel construction wherein the number of points of effective feeding contact or pressure upon the work have been increased and wherein an increased number of effective feeding contacts are maintained at the various stages where sticking of the work is likely to occur in sewing over a cross-seam. To this end there is provided a plurality of pivotally mounted sole-pieces, one in advance of the other, and the gist of the invention resides in supporting such sole-pieces, which I call secondary sole-pieces, upon a pivotally mounted primary member which latter is formed with one or more work-engaging surfaces, preferably at the sides of the zone acted upon by the so-called secondary sole-pieces. By virtue of this construction, feeding pressures are maintained not only upon the stitched zone of the seam but also at the sides of such zone, when sewing over a cross-seam; the effective feeding pressures at the sides of the stitched zone aiding materially in carrying the lump of the cross-seam under the foot.

It is also advantageous in some cases to

pivot the front secondary sole-piece so that it will yield bodily vertically relative to the primary member. It is further usually desirable when sewing felled seams to arrange the secondary sole-pieces in a longitudinally extending channel in the primary sole-piece, such channel accommodating the felled zone of the work. Further features of the invention will, in part, be obvious and, in part, be hereinafter described.

In the accompanying drawings, Fig. 1 is a side elevation of a sewing machine presser-foot embodying the invention. Fig. 2 is a top plan view of the presser-foot. Figs. 3 and 4 are respectively, front and rear elevations of the presser-foot. Fig. 5 is a bottom plan view. Fig. 6 is a perspective view of the presser-foot shank. Fig. 7 is a perspective view of the primary sole-piece. Fig. 8 is a perspective view of the forwardly disposed secondary sole-piece. Fig. 9 is a perspective view of the rearwardly disposed secondary sole-piece. Fig. 10 is a plan view of the sewing machine throat-plate and feed-dog. Fig. 11 is a side view similar to Fig. 1 showing a cross-seam passing under the forward end of the presser-foot and Fig. 12 is a similar view showing the cross-seam passing under the central portion of the foot.

According to the preferred embodiment of the invention illustrated, the presser-foot comprises a shank 1 adapted to be secured as usual to the vertically movable presser-bar 2 of a sewing machine having the reciprocating needle-bar 3 carrying needles 4, which operate in the needle-holes 5 in the throat-plate 6, which latter is slotted as usual to admit the toothed sections of the four-motion feed-dog 7.

The presser-foot shank 1 is formed with spaced depending arms 8 carrying trunnion screws 9 on which the primary sole-piece 10 is pivotally mounted. The primary sole-piece 10 comprises the spaced side-bars 11 having lower work-engaging faces 12. The side-bars 11 have their up-turned toe-ends connected by a transverse spacer bar 13, the under up-turned surface of which is spaced above the under surfaces of the side-bars to form a work-receiving channel 14, Figs. 2 and 5. The side-bars 11 are connected at their rearward ends by the pivot-pin 14 which supports the rearwardly disposed or trailing secondary sole-piece 15. The side-bars 11 are formed in advance of the pivot-

pin 14 with vertical bearing slots 16 for the alined pivot-extensions 17 at the opposite sides of the forwardly disposed or leading secondary sole-piece 18 having the needle-holes 19. The open upper ends of the bearing slots 16 are closed by the down-turned tip-ends of the leaf-springs 20 which are secured to the side-bars 11 and permit the forwardly disposed secondary sole-piece 18 to yield bodily vertically relative to the primary sole-piece 10. The secondary sole-pieces 15 and 18 are thus disposed in the recess or channelway 14 between the side-bars 11 of the primary sole-piece, and the leading secondary sole-piece 18 constitutes a yielding roof-section of said channelway. A leaf-spring 21 secured to the presser-foot shank 1 and bearing at its free end upon the toe-end of the trailing secondary sole-piece 15 is provided for preventing the heel-end of such sole-piece from dropping and interfering with withdrawal of the work from feed-on-the-cylinder machines, when the presser-foot is raised. The pivot-pins 17 are disposed in a line transverse to the direction of feed and substantially centrally of the transverse zone of the needles; i. e., equidistant from the front and rear needles. This arrangement secures the most uniform and best control of the work in the immediate transverse zone being stitched as the needles are sewing onto and off of a cross-seam. The danger of skipped stitches due to failure of a needle to throw out a loop when sewing in a loose or vertically movable portion of material is thus reduced to a minimum.

The operation of the presser-foot, embodying the invention in its preferred form, is substantially as follows: When sewing a felled seam for example, Fig. 1, the felled zone *b* of the work *a* is received in the channelway between the side-bars 11 of the primary sole-piece 10 and is pressed upon rather heavily by the trailing secondary sole-piece 15 and more lightly, if at all, by the leading secondary sole-piece 18. The side-bars 11 press at their toe-ends upon the work at the sides of the felled zone. Thus effective pressures are applied at three positions for the feed-dog 7 to work against; the leading secondary sole-piece 18 acting mainly as a stripper to hold the work against rising with the needles and thus insuring against the skipping of stitches. In Fig. 1 a cross-seam *c* presenting the usual lump *d* is shown approaching the foot.

As the cross-seam *c* passes under the toe-end of the foot it is seized by the front ends of the feed-dog sections and the primary sole-piece 10 is tilted sufficiently to admit the cross-seam *c*, without destroying the feeding pressures at the three positions herefore referred to. As the lump *d* passes under the toe-end of the leading secondary sole-piece 18, the latter is more abruptly

tilted, but as it does not press heavily upon the work at this time it does not seriously impede movement of the lump *d*. At a slightly later stage, Fig. 11, the lump *d* in passing further under the leading secondary sole-piece 18 causes the latter to yield vertically relative to the primary sole-piece 10, whereby an increased and effective feeding pressure of the sole-piece 18 is brought to bear directly upon said lump while effective feeding pressures are maintained by the primary sole-piece 10 at the sides of the lump and by the trailing secondary sole-piece 15 in rear of the lump. Thus feeding pressures are applied at four positions at this critical stage where resistance to passage of the cross-seam is usually greatest.

As the lump *d* passes the leading secondary sole-piece 18, the toe-end of the latter is tilted downwardly (Fig. 12) and holds the work closely under control to prevent skipping of stitches in the region immediately following the cross-seam. Effective feeding pressures are still maintained at the sides of the lump by the primary sole-piece 10 as well as upon the felled zone by the secondary sole-pieces. Following the stage shown in Fig. 12 the lump *d* is readily carried under the trailing secondary sole-piece 15 which tilts to maintain a feeding pressure at its heel-end as its toe-end is passing onto the lump *d*. When the cross-seam passes under the trailing secondary sole-piece 15 the primary sole-piece tilts downwardly at its front end and feeding pressures at such end are resumed.

While I have shown and described in detail a preferred embodiment of the invention, it is to be understood that the invention is not limited to a device having the details of construction and precise mode of operation described. To handle seams of different character and work of various thicknesses, the pressure applying sections of the foot may be varied in form and arrangement within the scope of the invention, as will be understood by those skilled in the art.

Having thus set forth the nature of the invention, what I claim herein is:

1. A sewing machine presser-foot having a shank, a primary sole-piece pivotally mounted on said shank and having a work-engaging surface, and a plurality of secondary sole-pieces pivotally mounted one in advance of the other on said primary sole-piece. 115

2. A sewing machine presser-foot having a shank, a primary sole-piece pivotally mounted on said shank and having a work-engaging surface, and a plurality of secondary sole-pieces pivotally mounted one in advance of the other on said primary sole-piece, the forwardly disposed secondary sole-piece being bodily yieldable vertically relative to said primary sole-piece. 125

3. A sewing machine presser-foot having 130

- a shank, a longitudinally channeled primary sole-piece pivotally mounted on said shank, and a plurality of secondary sole-pieces pivotally mounted on said primary sole-piece 5 and disposed one in advance of the other in the channel in said primary sole-piece.
4. A presser-foot having a shank, a primary sole-piece pivotally carried by said shank and presenting spaced rigidly connected side-bars having lower work-engaging surfaces, and leading and trailing secondary sole-pieces pivotally carried one in advance of the other by said primary sole-piece and disposed between the side-bars of the latter. 10
- 15 5. A sewing machine presser-foot having a shank, a primary sole-piece pivotally mounted on said shank and comprising spaced side-bars having work-engaging surfaces, and a secondary sole-piece pivotally mounted on said side-bars to work intermediate the latter, the pivotal axis of said secondary sole-piece being bodily yieldable 20 vertically relative to said side-bars.
- 25 6. A presser-foot having a shank and a sole-piece pivotally carried by said shank, said sole-piece having in its under face a longitudinally extending channelway for re-
- ceiving a felled-seam, and a yielding roof-section disposed in said channelway and at all times above the work-engaging surfaces 30 at the sides of the channelway in said sole-piece.
7. A sewing machine presser-foot having a shank, a primary sole-piece pivotally mounted on said shank and comprising 35 spaced side-bars rigidly connected together, and a plurality of secondary sole-pieces pivotally mounted on said primary sole-piece one in advance of the other, the leading secondary sole-piece being bodily yieldable 40 vertically relative to said primary sole-piece.
8. A presser-foot for sewing machines comprising a sole-piece having at its opposite sides outwardly extending pivot-pins rigid therewith, a supporting member having vertical bearing slots for said pivot-pins, said slots having lower closed ends, and springs bearing down upon said pivot-pins to normally press them into contact with the lower 45 closed ends of said slots. 50

In testimony whereof, I have signed my name to this specification.

GEORGE S. GATCHELL.
